UNITED STATES PATENT OFFICE.

LOUIS K. JOHNSON AND A. AUGUSTUS LOW, OF BROOKLYN, NEW YORK.

TYPE-SETTING APPARATUS.

SPECIFICATION forming part of Letters Patent No. 271,711, dated February 6, 1883.

Application filed December 30, 1881. (No model.)

To all whom it may concern:

Be it known that we, LOUIS K. JOHNSON and A. AUGUSTUS LOW, both of the city of Brooklyn, in the county of Kings and State of New York, have invented certain new and useful Improvements in Type-Setting Apparatus, of which the following is a specification.

Our improvements relate to that class of type-holders in which the type is presented to the compositor for removal in prescribed positions from the lower ends of containing-channels.

The object of our present improvements is to embody in a single compact apparatus essential devices requisite in the art of type-setting in such manner that they may be readily adjusted and employed with relation to each other, and to adapt them to the convenience of compositors of different heights.

Our invention consists, first, in bed-plates for supporting the type-containing channels, formed so as to interlock with and sustain each other when superimposed; secondly, in a channel-holder secured to a double or universal joint, consisting of two independently-adjustable joints working in planes at right angles to each other and interposed between the channel-holder and its support, so that the holder may be accurately adjusted to any angle; thirdly, in the special construction and arrangement, with the channel-holder, of an auxiliary compartment-case for holding extra types of denominations that are seldom used—as capitals, italics, &c.—mounted upon the top of the channel-holder in such manner that it may be readily slid up and supported out of the way when not in use, or as readily lowered and sustained in a position convenient for use by the compositor; fourthly, in a combined copy-support and quad-holder, mounted adjustably upon the side of the channel-holder, so as to be capable of regulation both vertically and laterally with relation to the position of the compositor; fifthly, in a vertically-adjustable galley-holder, mounted upon the standard or base in such manner that it may be swung around to the front for use in correcting, or secured out of the way at the rear of the apparatus.

In the accompanying drawings, Figure 1 is an isometrical perspective of our improved

compositor's apparatus; Fig. 2, a side elevation of the upper portion of the same, showing the auxiliary type-case in section and the side casing of the channel-holder removed to expose the arrangement of the bed-plates; and Fig. 3 an isometrical perspective of one of the bed-plates removed.

The upper end of the base or standard A is hollow to provide for the reception of the vertical screw S, upon which the type-holder H H' is mounted. This screw is elevated or depressed by means of a hand-nut, N, bearing against the top of and extending down a short distance into the standard A. The adjustability thus attained is of importance in adapting the type-holders to either the standing or sitting positions, or to the varying heights of different users. This construction also allows the type-holder to be readily turned laterally to adapt the case to variations in light, or to other circumstances.

Between the top of the screw S and the bottom of the channel-holder H we interpose two adjustable joints, J J', provided with binding-screws j j' and working in planes at right angles to each other, together forming a universal joint which will admit of the accurate adjustment of the channel-holder to any angle required. This facility of accurate adjustment is of importance in regulating the inclination of the containing-channels, so as to relieve the bottom of a column of type as much as possible from the pressure of the upper portion, and in regulating the "tilt" or lateral inclination given to the channels in order to prevent the type escaping from their open edges.

The channel-holder H is composed of a series of flanged bed-plates, h, which are superimposed, as shown in Fig. 2, and to the upper sides of which the supporting-ribs and channel-seats h' are affixed.

The relative arrangement, construction, and operation of the type-channels C and their seats h' are substantially the same as those shown and described in the applications for patents of Louis K. Johnson, filed respectively upon July 11, 1881, and October 24, 1881, and therefore is not here shown in detail.

The base-plates h are provided with flanges h² at each side, which separate the bodies of the adjacent plates from each other sufficiently

to allow the insertion or removal of the type-containing channels into or from position from the front of the apparatus. They are also formed with coinciding interlocking projections or shoulders h^3 and recesses h^4 , by which means they are made to support each other against relative displacement, and when bound together by one or more bolts, h^5 , become practically as rigid and substantial as though made in one piece.

In adapting the principle of presenting type to the hand-compositor in containing-channels arranged in close proximity to each other to the construction of cases suitable for ordinary composing, it has been found both sufficient and expedient to provide accommodation in the case for about one hundred characters; but there are still other denominations of type that are, comparatively speaking, only occasionally required, which it would still be desirable to have within convenient reach, as italics, small caps., &c. To provide containing-channels for these extra characters in the body of the case itself would nearly double its dimensions and add materially to the cost, all of which we avoid by adapting the top of the channel-holder to receive and support the auxiliary type-case H' , which is provided with a sufficient number of compartments to accommodate the said extra characters. This auxiliary case H' is held in place laterally by and slides between the shoulders or flanges $i i$, projecting from the channel-holder H . Ordinarily when not in use the auxiliary case is supported entirely above and beyond the front of the channel-holder, out of the way, as shown in Fig. 1; but when required temporarily for use it is slid down into the position indicated by dotted lines in Fig. 2, when all its compartments are within convenient distance of the compositor. In order to provide for its support in either of these two positions, the auxiliary case is provided with two series of projections or tongues, $u u$ and $d d$, one set, $u u$, near its lower front edge, which, when engaged with the hooks $k k$ upon the top of the channel-holder, support it when not in use, and the other set, $d d$, near its upper rear end, which support it in a similar manner when lowered for use.

Mounted at the side of the channel-holder H is the combined copy-support and quad-holder Q . This is adjustable both laterally and vertically upon the rod q , (secured to the side of the channel-holder,) so that it may be raised or lowered or swung forward at any angle for use, according to the convenience of the compositor, or backward against the channel-holder when not in use. Its upper portion is provided with a counterbalanced copy-mark, r , and its lower portion is formed with an inclined compartment, t , for receiving and presenting the quads.

Brackets $b b$, formed with suitable notches or seats, $b' b'$, to receive the thickness of a containing-channel, are affixed to opposite sides of

the channel-holder H , and furnish a temporary support for a channel when from any cause it is desirable to examine or adjust the column of type contained therein or while substituting and arranging the channels.

Attached to the same support as the channel-holder, and immediately below the latter, is a bracket, G , which furnishes bearings or seats for a series of cup-shaped space-receivers, $o o o$. During the operation of "justifying" the lines as they are formed in the stick, spaces that have been placed therein have necessarily to be discarded from time to time and others substituted in their place, and these receptacles $o o o$ are for the purpose of furnishing a convenient means of disposing of these discarded spaces quickly by simply dropping them into one or the other of the series, according to their denomination, thereby obviating the necessity of subsequent distribution or separation. The bracket G also furnishes a support for the inclined flanged rest or shelf L , which may be made to answer the purpose of a temporary galley, or when not so employed as a rest for the stick or other implements used by the compositor.

Mounted upon a shoulder, a , on the standard A is a swinging arm or bracket, B , on the outer extremity of which is mounted a vertically-adjustable galley-holder, D . When not in use, or when so required, the galley-holder is swung back out of the way and secured in such position by tightening the set-screw b^2 against the standard A ; but when, in correcting or for other cause, it is desirable to have the galley in front of the case, the arm B is swung around into that position and the galley-holder D adjusted vertically to suit the convenience of the operator.

One or more channel-racks, $R R$, are secured to the rear side of the lower portion of the standard A , and furnish a convenient and compact arrangement for the storage of the channels, ready for use.

To support the channels vertically upon their closed edges, and thereby avoid the displacement of the columns of type contained therein, we provide each channel-rack with a series of projections or tongues, w , the spaces between which correspond exactly to the width of a channel.

What we claim is—

1. The superimposed bed-plates h , formed with the spacing-flanges h^2 , and having the channel-supporting seats h' secured to their upper surfaces, substantially in the manner and for the purpose described.

2. The superimposed bed-plates h , having the channel-supporting seats h' secured to their upper surfaces, and formed with spacing-flanges h^2 , and coinciding interlocking projections or shoulders h^3 , and recesses h^4 , substantially in the manner and for the purpose designated.

3. A type-containing channel-holder, substantially such as designated, secured to a

- double or universal joint, $J J'$, interposed between said channel-holder and its supporting column or standard, substantially in the manner and for the purpose described.
- 5 4. The auxiliary type-case H' , formed with two series of projections or tongues, $u u$ and $d d$, one set near its lower front end and the other set near its upper rear end, in combination with and mounted adjustably upon the top of the type-containing channel-holder H , formed with the flanges $i i$ and the hooks or catches $k k$, for the purpose and substantially in the manner herein set forth.
- 5 5. In combination with a type-containing channel-holder, substantially such as desig-
- nated, the combined copy-support and quad-holder Q , secured to and adjustable upon the side of the said channel-holder, substantially in the manner and for the purpose described.
6. In combination with a type-containing channel-holder, substantially such as designated, and its supporting-standard A , the swinging bracket B and vertically-adjustable galley-holder mounted thereon, substantially in the manner and for the purpose described.
